UNITED STATES PATENT OFFICE.

EDWARD O'TOOLE AND HOWARD N. EAVENSON, OF GARY, WEST VIRGINIA.

REMOVING COAL FROM MINES.

957,364.

Specification of Letters Patent. Patented May 10, 1910.

Application filed May 19, 1909. Serial No. 497,111.

To all whom it may concern:

Be it known that we, EDWARD O'TOOLE and HOWARD N. EAVENSON, residing at Gary, in the county of McDowell and State of West Virginia, citizens of the United States, have invented or discovered certain new and useful Improvements in Removing Coal from Mines, of which improvement the following is a specification.

10 The invention described herein relates to certain improvements in removing coal from mines.

It has been proposed to effect a removal of coal by conducting air under a high pressure to the point where the coal is mined, and to introduce the coal in a finely divided state into the returning current of air in another conduit or pipe of considerable dimensions. The method is however impracticable, 20 as the cost of maintenance of a working pressure sufficient for the long distances, amounting to miles in some cases, is prohibitive.

The invention described herein has for its object a step by step transfer of the coal by outwardly flowing currents of air preferably produced by exhaust fans connected to a series of two or more entries one of which is utilized for the transfer of the coal.

The invention is hereinafter more fully 30 described and claimed.

In the accompanying drawings forming a part of this specification Figure 1 is a dia- 35 grammatic view illustrating an arrangement of locks etc. in the heading or entries of a mine and connections between such head- 40 ings or entries whereby a movement of coal by air currents from the machine to the mouth of the mine is effected; Fig. 2 is a sectional view showing a machine in position 45 at the inner end of a heading or entry, and showing a desirable manner of feeding the coal to the outwardly flowing current of air; Fig. 3 is a sectional plan view of a lock, Figs. 4 and 5 are sectional elevations on planes indicated respectively by the lines IV-IV and V-V Fig. 3; Figs. 6 and 7 are sectional views showing a suitable arrangement of storage bins for shaft and drift mines, and Fig. 8 shows end and plan views of a nozzle 50 for the reception of the coal at the machine.

In the practice of our invention the coal is removed from the vein or body of coal in a finely divided state, although, without departing from the invention described here-

in, it may be mined in lumps which can be 55 subsequently reduced to the desired size by any suitable means. When the coal is removed in a finely divided condition, a receiving nozzle 1 having a length approximately equal to the width of the cut made 60 by the machine is arranged at the foot of the breast of coal, so that the finely divided coal will be swept by the current of air through a slot 2 lengthwise of the nozzle. This nozzle is connected by a tube 3 having 65 a telescopic section 4 to the entry or heading 5 which it is designed to utilize for the outward movement of the coal. This entry will for convenience be termed the transfer entry. The tube is connected to the entry 5 70 by a lock formed in the entry and completely closing the same, except for the passages and chambers hereinafter described. From the tube 3 the air and coal enter a comparatively large chamber 6 permitting an expansion 75 and consequent slowing down of the rate of flow, to such an extent that the coal will settle down into the bin 7, the air freed from the coal flowing through a passage 8 into the entry 9 parallel with the entry 5. 80

As shown the entry 5 used for the transfer of the coal, is intermediate of entries 9-9^a etc. and 10-10^a etc., the former being connected at their outer ends to any suitable form of exhaust apparatus whereby outward 85 currents of air of desired velocity may be maintained in the entries 9-9^a etc. The entries or headings 10-10^a etc., serve as intakes for the air.

As shown in Fig. 1 the heading or entry 90 5 is divided by locks into sections of a length dependent upon the carrying capacity of the current of air employed, and the number of sections will depend upon the distance from the point where the coal is mined to 95 the mouth of the entry or heading. The locks are formed by a transverse wall 11 closing the entry or heading except adjacent to the roof of the latter. Beyond this wall toward the mouth of the entry the latter is divided into upper and lower chambers 12 and 13 by a horizontal hopper-like partition 14, the upper surface of which slopes to an opening through the partition. This opening is normally closed by a movable door 15 held closed by suitable means as a weight 16, which will permit the door to open as soon as the desired amount of 100 105

coal has accumulated in the bin formed by chamber 12. At a suitable distance beyond the bin, the transfer entry is closed by a transverse wall 17 and from the chamber 13 below the bin a tube 18 extends through the wall 17 preferably at a point near the roof of the entry. The chamber 13 below the bin is connected in any suitable manner, as by a tube 19, to one of the intake entries or headings 10-10^a etc. The expansion chamber 12 containing the bin is connected in any suitable manner, as by a branch passage 8, to the out-take or exhaust passages 9-9^a etc.

As the coal-laden currents of air flow from the tube 3 or one of the sections of the transfer entry or heading 5 into the expansion chamber through the opening above the wall 11 its rate of flow will lessen to such an extent that the coal will drop into the bin. From the expansion chamber the air freed from the coal will flow from the expansion chamber by the branch 20 into the exhaust or out-take entries or headings, so as to maintain an outward flow of air through the section or tube behind the lock through which the air and coal entered the expansion chamber.

After the desired amount of coal has accumulated in the bin the door 15 will drop, allowing the coal to flow down into chamber 13 where it will encounter and be carried on by a current of air flowing from the intake 10-10^a etc. through the tube 19 and out through the tube 18 into the next section of the transfer entry or heading and to the next lock, where the rate of flow of this current is checked and the coal deposited in the bin of said lock. This step by step movement of the coal insures a practically uniform rate of movement from the mining machine to the storage bin at the mouth of the mine, and by separating the coal from a current of air before a detrimental retardation occurs and causing it to be carried forward by another current having a rate greater than that of the first current at the time when the coal is separated from it, the average rate of movement will be high. The headings or entries 9-9^a are large as compared with the passage in the entry or heading 5 through which the coal moves, so that by employing such entries or headings as exhaust passages a comparatively high velocity of air can be maintained with a minimum expenditure of power. Although any given quantity of coal is frequently stopped in its movement to the mouth of the mine, there will be a constant movement of coal throughout the whole distance.

It will be understood that the vacuum or out-take entries will not have any connection with the transfer entry except at the locks. The in-take entries are connected to the transfer entry not only at the locks but also at some point between the first lock and

the point where the machine is operating, so that there may be a flow of air in through the nozzle 1.

In adapting our method to any mine it is believed that a vacuum represented by about fourteen inches of the barometer will produce a sufficient rate of flow of air for the sectional transfer of the coal, but it will be understood that lower vacuum and a higher rate of flow can be employed. At the beginning of the operation the first section of the transfer entry will begin to fill up from the end where the coal and air enter, and this filling will continue until only a comparatively small passage through the section remains. The transverse dimensions of this passage will depend upon the velocity of the current employed. This filling up will continue from section to section until a passage proportioned to the rate of flow is formed throughout the entire length of the transfer entry 5. After the formation of the passage the movement of the coal will be continuous and uniform, while the vacuum remains stationary. In case the vacuum is increased, producing a higher rate of flow of air, the air will pick up some of the coal previously deposited, thus enlarging the passage through the entry proportional to the increased rate of flow. If the rate of flow is decreased there will be a gradual and progressive filling up of the passage until its dimensions are again brought to operative limits.

After the establishment of the locks and their connections to the out-take and in-take entries the operation of moving the coal will be entirely automatic except for the insertion of new lengths in the tube 3 connecting the inlet nozzle 1 with the first lock of the series, as the mining machine moves in. The cost of operation will be little if any in excess of that now incurred in the ventilation of the mines by the exhaust fans.

It will be readily understood by those skilled in the art that in lieu of forming the passages through which the coal is carried, by partially filling the entries or headings, said passages may be formed by tubes extending along the entries or headings. But in such case the tubes will have internal dimensions proportional or approximately proportional to the rate of the current of air to be employed in the transfer of coal.

The outer end of the outer section of the transfer entry is formed by a storage bin 21 of sufficient capacity having suitable discharge chutes 22 for directing the coal into cars. This bin is connected to the exhaust apparatus, and if desired, the entire exhaust from the mine can be through the storage bin, the out-take or vacuum entries being connected thereto, or both the bin and the out-take entries can be connected to the exhaust apparatus.

The term "passage" is used herein generically and includes a continuous opening whether formed by partially filling a heading or entry, or formed by a tube extending along a heading or entry.

It will be readily seen by those skilled in the art of mining that this pneumatic system of conveying coal at the same time furnishes the most perfect system of ventilation that can be devised. The air enters the mine through the passages 10, 10^a etc., moving in them with moderate velocity, and is conducted directly to the face of the working place without employing any brattices or other means of directing its motion. At the face of the working place, where it enters the tube, the velocity is enormously increased and any gas that may be given off by the coal and all dust created by the mining machine, will be instantly carried into the tube with the coal. The capacity of the tube in each working place will be ample for even the most gaseous place. In addition to the air flowing at the face of each working place, a quantity of air will be withdrawn from the headings 10, 10^a etc., at each lock, thus causing a constant circulation of fresh air throughout the mine.

It will be readily understood that with this system of mining all danger of explosions caused by gas or dust will disappear, and there will be no necessity of using safety lamps in the working places, as all gas will be instantly carried off through the passages and that no stoppings or brattices will be required.

We claim herein as our invention—

1. As an improvement in the art of removing coal from mines a method which consists in subjecting the coal to a series of currents of air at atmospheric pressure acting in succession thereon.

2. An improvement in the art of removing coal from mines which consists in admitting air having a pressure not greater than atmospheric pressure to a passage extending along the mine at different points there along, withdrawing the air from the passage at a lower pressure and at points distant from

the point of admission, thereby forming a series of streams or currents of air flowing outwardly along the passage, and feeding coal in a finely divided condition to such currents.

3. An improvement in the art of removing coal from mines which consists in establishing in the mine a series of outwardly-flowing currents of air at or approximately at atmospheric pressure and feeding the coal to such currents of air in succession.

4. An improvement in the art of removing coal from mines which consists in causing a current of air to move outwardly in the mine, feeding coal in a finely divided state to such stream, and automatically changing the dimensions of the passage traversed by the air in accordance with variations in the rate of flow of the air current.

5. A mine consisting of a heading or entry for the reduction of air pressure, another heading or entry for the free inflow of air, a third entry divided into sections, and means for the admission of air from the intake entry to the forward end of each section, and means permitting it to escape into the out-take entry at the rear end of each section.

6. A mine consisting of an entry extending to the working face and divided into a plurality of sections, a second entry connected to such sections, means for reducing the pressure of air in such second entry and a third or intake entry extending to the working face and connected to the said sections, whereby air is caused to flow into the working face and outwardly therefrom.

In testimony whereof, we have hereunto set our hands,
